UNITED STATES PATENT OFFICE.

CORNELIUS B. CORCORAN, DECEASED, LATE OF NEW YORK, N. Y.; BY MICHAEL J. CORCORAN, ADMINISTRATOR, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed June 28, 1924. Serial No. 722,482.

To all whom it may concern:

Be it known that CORNELIUS B. CORCORAN, deceased, late a citizen of the United States, and late residing in the borough of Bronx, 5 county of Bronx, city and State of New York, invented certain new and useful Improvements in Typewriting Machines, of which the following is a specification.

This invention relates to typewriting 10 machines of the front-strike type, in which the type-bars are mounted on a curved wire carried by a segment. Usually the blows of the type-bar are stopped, just before contact of the types with the platen, by a 15 rigid portion of the type-bar segment to avoid the tendency of the type-bar to chatter and make repeated impressions on a work-sheet, the type-heads springing beyond a stop sufficiently to deliver a whip-like blow 20 upon the work-sheet.

Such impact of the metal surfaces produces an annoying clattering noise of considerable intensity, and it is therefore one 25 of the features of this invention to provide an improved separate stop designed to deaden such sounds without lessening the advantages of a rigid anvil or type-bar stop formed directly on the segment.

It is a further feature to provide a stop 30 readily removable when worn, that is moderately yieldable, tending to reduce the shock of the type-bar and preventing it from being transmitted to other parts of the machine, thus further reducing the noise 35 of operation.

The simple and inexpensive type-bar stop can be readily applied without any changes in the typewriting machine.

These features are accomplished by securing 40 a segmental spring stop upon the face of the segment, in which the type-bars are pivoted, making use of openings which already exist therein for attaching purposes, the stop being provided with sound-reducing means known to be effective and so mounted as to prevent the emission of noise to a marked extent.

Other features and advantages will hereinafter appear.

50 In the accompanying drawings,

Figure 1 is a front elevation of a type-bar segment as used with a machine of the

Underwood type, showing an embodiment of the invention as applied, the platen appearing in dot-and-dash lines.

55 Figure 2 is a transverse sectional view of the same, the section being taken on line 2-2 of Figure 1, and a type-bar shown in dot-and-dash lines as connected to the segment, both in raised and lowered positions.

60 Figure 3 is a view similar to Figure 1, but showing a modified form of the stop-bar anvil.

65 Figure 4 is a transverse sectional view, taken on line 4-4 of Figure 3.

In the accompanying drawings, such parts of a typewriting machine are shown as relate only to the invention, all other parts being of ordinary construction and unrelating to this disclosure.

70 The platen, generally designated by the numeral 10, is of the cylindrical type, shiftable into upper and lower case position to receive the impact from the type characters carried on type-heads 11, these heads being fixed on free ends of type-bars 12 pivoted on a rod 13 and actuated by links 14 engaging the bars near their pivoted ends.

75 The type-bars shown are of the Underwood style, and the links 14, as will be understood, are moved by their connections with key-actuated levers on the keyboard of the machine in the ordinary manner, such parts being omitted from the drawings.

80 The rod 13 is mounted in the lower part of a type-bar segment 15, the same having slots 16 to actuate the type-bars 12 and an extending rib 17 adjacent to which the type-bars move when in position to make an impression on the platen. The segment 15 is 85 fixed rigidly by screws 18 to a front portion of the typewriting machine frame, indicated by the numeral 19, the construction of the machine being well known.

85 As shown in Figures 1 and 2, a stop comprising two similar but oppositely-disposed metal elements 21, recessed at their abutting ends to receive a strap-like connector 22, is held to the reduced portions of the stop elements by rivets 23 forming a secure and 90 rigid joint fastening.

95 This joint is found in practice to materially aid in reducing the transmission of sound, due to the impact of the type-bars upon the

stop, and to further reduce the noise the stop is drilled partially through its inner side to produce openings 24.

The outer ends of the top elements are 5 materially widened at the curved ends 25 from which extend arms 26 concentrically spaced from the lower convex edges of the stop and terminating in pads 27, which are slightly offset towards the supporting surface 20, or, if preferred, provided with washers 28, to raise the smooth lever under surface of the stop slightly away from the surface 20, such offset presenting a space 30 of only a few thousandths of an inch 10 in extent, and passing through a perforation in each pad are binding screws 29 holding the stop firmly in engagement with the segment.

From the foregoing it will be clear that 20 when a type-bar strikes the stop, the stop will be momentarily deflected to make contact with the face of the segment, recovering instantly after the impact, such yielding of the stop in no wise interfering with 25 its arresting effect, but serving to cushion the blow to prevent sound emission, such silencing effect being increased due to peculiarity of its structure.

In the modification shown in Figures 3 30 and 4, the stop 31 is integrally formed from a single piece of metal having broadly curved ends 32 from which extend arms 33 spaced closely concentric to the curved lower edge of the stop, and being offset at 35 their ends 34 through which pass screws 35 securing the stop spaced from the face of the segment 15 in the manner before described.

The inner adjacent side of the stop contains a plurality of closely-spaced openings 36 extending partially through the material of the stop, and set firmly in each opening is a plug 37 of relatively soft, dense material, as lead, acting to reduce the vibrant 45 quality of the metal stop and to correspondingly lessen the sound of the type-bar blow so that the same is negligible.

Variations may be resorted to within the scope of the invention, and portions of the 50 improvements may be used without others.

Having thus described the invention, I claim:

1. The combination with a typewriting machine having type-bars and a segmental support therefor, of an arcuate stop fixed to the face of the support at a spaced distance therefrom, said stop having a plurality of closely spaced recesses in its under surface, said stop being mounted to spring 55 against the support when struck by a type-bar, and a lead plug fixed in each of the mentioned recesses.

2. The combination with a typewriting machine having type-bars and a segmental

support therefor, of an arcuate stop having 65 spring arms secured at their ends to the face of the support, means for spacing the stop and arms slightly from the support, and means in the stop to reduce sound upon its being struck by a type-bar.

3. The combination with a typewriting machine having type-bars and a segmental support therefor, of an arcuate stop having 70 integral arms concentrically spaced from its convex edge, means at the ends of the arms to fasten the stop to the support, other means at the ends of the arms to normally retain the stop off the surface of the support, said stop yielding to contact with the support at each blow of the type-bars, and 75 sound nullifying means carried by the stop.

4. The combination with a typewriting machine having type-bars and a segmental support therefor, of a stop shaped to conform 80 with the support and intercept each of the type-bars at their impression strokes, said stop presenting a relatively narrow contact surface and containing a plurality of openings in its lower surface, arms integral with the 85 ends of the stop, said arms being curved to extend alongside the convex edge of the stop towards each other, and provided with openings to receive securing means engaged in the support, means at the ends of the arms to raise the stop minutely from the 90 surface of the support, and leaden plugs fixed in the mentioned openings.

5. The combination with a typewriting machine having type-bars and a segmental support therefor, of a stop shaped to conform 95 with the support and intercept each of the type-bars at their impression strokes, said stop being composed of two like sections arranged in opposed relation, each section having openings in their under surfaces and re-entrantly turned arms at their ends, means at the ends of the arms by which the stop may be secured to the support, other means for holding the stop minutely spaced from the support, and means for uniting 100 the adjacent ends of the stop sections.

6. The combination with a typewriting machine having type-bars and a segmental support therefor, of a stop shaped to conform 105 with the support and intercept each of the type-bars at their impression strokes, said stop being composed of two like sections arranged in opposed relation, each section having openings in their under surfaces and re-entrantly turned arms at their 110 ends, means to spacedly secure the arms to said support, and a plate riveted to the inner adjacent ends of the sections, said plate being level with the under surface of the stop.

MICHAEL J. CORCORAN,
Administrator of the estate of Cornelius B. Corcoran, deceased.
